UNITED STATES PATENT OFFICE.

GEORGE W. MEGNIN, OF ALLENDALE, NEW JERSEY.

ACCELERATOR CUSHION.

Application filed July 23, 1926. Serial No. 124,540.

This invention relates to cushion devices for accelerators of internal combustion engines used on automobiles and other places and has for an object to provide a construction which may be readily adapted to any accelerator rod or accelerator connection associated with a carburetor.

Another object of the invention is to provide a cushion device for accelerator rods wherein means are presented which will cause a more even action in opening and closing the valve of a carburetor.

A further object, more specifically, is to provide in an accelerator rod a cushion wherein the power in both drums is communicated through resilient members.

In the accompanying drawing—

Figure 1 is a fragmentary view in outline of part of an automobile with a cushion embodying the invention shown applied to the accelerator rod.

Figure 2 is an enlarged sectional view through the cushion shown in Figure 1, the same being shown associated with parts of the accelerator rod.

Figure 3 is a sectional view through Figure 2 on line 3—3.

Referring to the accompanying drawing by numerals, 1 indicates an automobile provided with a carburetor 2 of any desired or usual construction having an arm 3 operating the usual butterfly valve. A bifurcated fitting 4 is connected with the end of arm 3 so that when this fitting is moved back and forth the valve will be opened and closed. The fitting 4 is connected through a cushion 5 with the accelerator rod 6. In fact, the fitting 4 really forms ordinarily part of the rod 6 and the cushion 5 which embodies the invention has been inserted into the rod so that in effect it forms part of the rod when in use. Rod 6 is connected with the usual foot pedal 7 through a bell crank lever 8. A spring 9 continually acts to hold the valve of the carburetor substantially closed.

When it is desired to accelerate the engine, pedal 7 is depressed in the usual manner and power is transmitted therefrom to the valve of the carburetor for opening the same to a greater or less extent according to the depression of the pedal 7. Where rod 6 is solid throughout and the cushion 5 is eliminated, the valve of the carburetor is opened and closed but is opened as suddenly as the pedal 7 is depressed and also is closed suddenly so that the carburetor is caused to give sudden jumps or sudden discharges of extra mixture which causes an uneven action of the engine. To cause the valve to open more easily and in a cushioned manner, the structure 5 is provided which is shown in detail in Figures 2 and 3. As indicated in these figures, the cushion 5 is formed with a casing 10 having a thickened end 11 provided with a bore 12 through which the rod 6' extends. Rod 6' at one end is provided with threads 13 so that the fitting 4 may be screwed thereon and the lock nut 14 used for locking the parts together. The casing 10 at the opposite end to the thickened portion 11 is provided with internal threads so as to be screwed onto the threaded section 15 of the block 16. Said block 16 is provided with a bore for receiving the end of rod 6, which rod is clamped therein by a set screw 17, though some other fastening means can be provided without departing from the spirit of the invention. In the casing 10 are arranged springs 18 and 19 which preferably are continually under slight compression though they could be relaxed. As shown in the drawing, these springs are under slight compression and bear against the respective ends 20 and 21 and also against the abutment 22 which is preferably integral with the enlargement 23 of rod 6' though it could be made separate and rigidly secured thereto. The abutment 22 is provided with one or more passageways or apertures 24 whereby oil or other lubricant as well as air in casing 10 can pass from one side of the abutment 22 to the other side as the device functions. When the pedal 7 is pressed down to an appreciable extent, rod 6 will press against block 16 and casing 10 so that the spring 18 will be brought under greater compression and will move the rod 6' and parts connected therewith, though not with the same suddenness that would ordinarily occur when pedal 7 is depressed. This will cause a smoother opening of the valve in carburetor 2 and, consequently, cause the engine to pick up in a much better way. As pedal 7 is gradually released or if it is suddenly released, spring 9 will move the parts back to their normal position, namely, the position shown in Figure 2. It will be noted that the back and forth movement of rod 6' and parts connected therewith is continually cushioned

by the springs 18 and 19 and that all power is transmitted through these springs. If pedal 7 was depressed slowly and evenly, all parts would remain in position as shown in Figure 2 through the entire movement of the butterfly valve and the same if returned in like manner. When pedal 7 is depressed sharply and jerkily, as in going over rough roads, coil spring 18 will be compressed in 10 degree according to amount of movement of pedal 7, in other words, under this type of action of pedal 7, springs 18 or 19 will absorb the shock of this uneven movement according to which way the pedal 7 is moving. If pedal 7 was sharply depressed and held at that point, spring 18 would compress some and when pedal 7 came to rest, spring 18 would recover its original position, thereby continuing the opening of butterfly valve 20 until parts reach position as in Figure 2, giving the smooth action desired. The purpose of enlargement 23 on both sides of abutment 22 is that if a sudden or absolutely sharp opening was required, as if pedal 7 was suddenly pushed all the way down, enlargement 23 would strike block 16 and force the carburetor open at once if the springs did not act quick enough for this emergency. Enlargement 23 strikes the end 30 11 when the spring 9 draws pedal 7 back when the foot is taken off, thus relieving any strain on spring 19; also compelling a firm and tight closing of the butterfly valve. Springs 18 or 19, according to the direction 35 of movement of pedal 7, absorb the shock of pedal 7 and some of the movement and in recovering itself, as it must and will, continues the movement imparted to pedal 7 until the parts come to rest as in Figure 2, 40 thereby giving a soft smooth operation.

What I claim is:

1. An accelerator cushion including a casing having an opening at one end, a rod receiving block removably connected to the other end, a sliding abutment arranged in the casing formed with an aperture extending therethrough, means extending from said abutment through said opening so as to connect said abutment with an adjacent object, and a spring on each side of said abutment for resiliently holding the abutment centered, the aperture in the abutment permitting air and lubricant to pass from one side of the abutment to the other as the abutment is moved. 50 55

2. A combined accelerator rod and cushion for automobiles comprising a rod divided into two parts, each part having means for connection to an object, one of said means being adapted to connect the rod with an accelerating pedal and the other of said means acting to connect the device with the accelerator valve of a carburetor, and a cushion structure into which the abutting ends of said parts extend, said cushion structure comprising a casing having a passage-way at one end through which one part of said rod extends, an apertured abutment on said last mentioned part arranged in said casing, a pair of springs arranged in said casing, one spring being arranged on one side of said abutment and the other spring arranged on the opposite side of said abutment, a block removably connected to said casing at the end opposite said passage-way, 75 and means for connecting the second part of said rod to said block. 60 65 70
